US00D563938S

(12) **United States Design Patent** (10) **Patent No.:** **US D563,938 S**
(45) **Date of Patent:** **** Mar. 11, 2008**

(54) **MOBILE PHONE**

(75) Inventors: **Bo-Ra Kim**, Seoul (KR); **Beom-Ku Han**, Seoul (KR); **Chang-Soo Lee**, Incheon (KR)

(73) Assignee: **Samsung Electronics Co., Ltd.**, Suwon-Si (KR)

(**) Term: **14 Years**

(21) Appl. No.: **29/274,853**

(22) Filed: **May 31, 2007**

(30) **Foreign Application Priority Data**

Apr. 11, 2007 (KR) 30-2007-0015831

(51) **LOC (8) Cl.** **14-03**

(52) **U.S. Cl.** **D14/138**

(58) **Field of Classification Search** D14/137, D14/138, 147, 148, 150, 168, 191, 218, 247-248, D14/341-347, 496; D10/65; D13/168; D18/7; 455/90.3, 556.1, 556.2, 575.1, 575.3, 575.4; 379/433.01-433.13; 361/814; 348/14.02

See application file for complete search history.
